UNITED STATES PATENT OFFICE.

ALEXANDER HART, OF NEW YORK, N. Y.

DESIGN FOR FUR TRIMMING.

SPECIFICATION forming part of **Design No. 21,547**, dated **May 17, 1892**.

Application filed March 22, 1892. Serial No. 425,999. Term of patent 14 years.

To all whom it may concern:

Be it known that I, ALEXANDER HART, a citizen of the United States, residing at New York, in the county and State of New York, have invented and produced a new and original Design for Fur Trimming, of which the following is a full, clear, and exact specification, reference being had to the accompanying drawing, forming part thereof.

The figure is a side elevation of fur trimming embodying the design.

The leading feature of the design consists of the braided band-like figure A and the fur band-like figure B, arranged on one side of

the said braided band-like figure A and having its hair C standing approximately at right angles to the said braided band-like figure A, thus giving a unique and highly ornamental appearance to the trimming, as is illustrated in the drawing.

I claim—

The design for fur trimming, herein shown and described.

ALEXANDER HART.
